UNITED STATES PATENT OFFICE.

EXEQUIEL PEDRO PAZ, OF BUENOS AIRES, ARGENTINA.

ADDRESS-PRINTING MACHINE.

1,333,773.

Specification of Letters Patent. Patented Mar. 16, 1920.

Application filed April 6, 1917. Serial No. 160,318.

To all whom it may concern:

Be it known that I, EXEQUIEL PEDRO PAZ, newspaper proprietor, a citizen of the Argentine Republic, residing at Calle Maipú 5 671, Buenos Aires, Argentine Republic, have invented a new and useful Address-Printing Machine, of which the following is a specification.

This invention relates to a machine for 10 addressing newspapers or the like, preferably by printing the address directly thereon, and for folding the paper and otherwise preparing it for transmission through the mails. The object of the invention is to 15 provide such a machine which will operate accurately and at a high rate of speed.

My invention will best be understood by reference to the following description of the 20 illustrative embodiment thereof shown in the accompanying drawings wherein:

Figure 1 is a plan view of a machine constructed in accordance with my invention;

Fig. 1^a is a central longitudinal section;

Figs. 2 and 3 are side elevations from the 25 right and left, respectively, of Fig. 1, simplified by the omission of remote parts;

Figs. 4 and 5 are end elevations as seen from the upper and lower sides, respectively, of Fig. 1;

Fig. 6 is a detail of the pneumatic nozzle utilized in a separating mechanism;

Fig. 7 is an elevation of a separating blade which works in conjunction with the nozzle and the operating mechanism there- 35 for;

Fig. 8 is a front elevation and a partial plan of the extracting gripper;

Fig. 9 is a central section through the partial plan in Fig. 8;

Fig. 10 is a side elevation and a plan of 40 the mechanism which handles the original pile of newspapers introduced to the machine;

Fig. 11 is a side elevation and plan of the 45 operating means for the separating blade illustrated in Fig. 7;

Fig. 12 is an elevation and plan of the guideway or galley for the printing plates and also shows the arrangement of the ink- 50 ing ribbon; and

Fig. 13 is a side elevation and plan of the feeding device for the printing mechanism.

I shall first describe in a preliminary way 55 the general operation of the machine here shown before entering upon a detailed description of its mechanical construction.

Herein a number of newspapers as delivered from the press are piled on a movable table from which they are successively removed, the paper at the bottom of the pile being 60 separated from the rest by means of suitable separating devices and seized and drawn out by a gripper similar in form to a pair of pincers. At a proper point in the motion of this gripper it releases the news- 65 paper, dropping it to a surface along which endless bands or tapes are passing at high speed and which position the newspaper against suitable gages for operation thereon of the printing mechanism. After the 70 printing operation the movement of the gripper in its regular cycle to the next news- paper effects a backward movement of the newspaper already acted upon, delivering it, to certain rollers and tape belts which carry 75 it to a folding knife or blade which folds the same and delivers it to a conveyer. All these operations are performed within a very short space of time constituting a cycle 80 of the machine. The printing is preferably effected by means of plates which may be suitably classified and stored in special receptacles provided as accessories of the machine, the plates being returned to said receptacles after the addresses have been 85 printed on the newspapers. The proper classification of the plates is thus preserved without difficulty.

Referring to the drawings, particularly to Fig. 1, the mechanisms here shown may take 90 motion through a suitable driving pulley 1 loose on the shaft 42 and adapted to be clutched thereto by clutch 38 operated by clutch lever 39 pivoted at 40 and positioned by the notched arm 41. In Fig. 2 is shown 95 the manner in which the principal shafts of the machine are driven from main shaft 42. The main shaft 42 carries a pinion 43 meshing with gear 2 on shaft 44. From shaft 44 the gear train 45, 75, 74, 73, 72, 71, 100 drives cam shaft 70, and cam shaft 132 takes motion from shaft 70 through intermeshing gears 71 and 164. The means by which other parts receive their motion will appear as the description proceeds.

I shall first describe the driving means for the gripper 52 which removes the newspapers one by one from the supply thereof. For operating this device I have here shown (Fig. 1^a) a crank wheel 17 on shaft 44 which 110 by means of the crank pin 46 and connecting rod 47 oscillates lever 48 pivoted at its lower

end at 49 to the frame of the machine and connected at its upper end by means of a link 50 to the transversely extending slide 14 (shown in detail in Fig. 8) which carries the grippers for removing the newspapers successively from a pile. The slide 14 is, as best shown in Fig. 1, guided in its travel by the lateral guides 9 and is provided with depending portions 51 working in slots in the table 61, which depending portions serve as gages to position the newspapers for the printing operation and serve also as means for advancing them toward the conveying bands which carry them to the folding device. As herein shown (Figs. 8 and 9), the grippers consist of an upper fixed jaw 52 and a lower movable jaw 53 mounted on a rock shaft 54 which is operated (Fig. 1^a) by a crank arm 55 provided with a roller 56 traveling in a slot in the vertically reciprocating slide 57, which slide has a cam follower 58 coöperating with a cam 35 (Figs. 1^a and 5). The reciprocation of the slide 57 causes the crank arm 55 to rock and the gripper jaws to open and close at proper times.

Coöoperating with the gripper are stops 59 (Figs. 1 and 1^a) carried by the arms 27 projecting inwardly from each side of the machine. The stops 59 engage the newspaper as the grippers recede toward the left to the position shown in Fig. 1^a and hold it in position as the jaws open. The newspaper is thus freed from the jaws and falls to the slotted supporting surface 61 in certain of the slots of which move the upper runs of the tape belts 24 traveling at high speed, to the left in Fig. 1^a, over the pulleys 60 which are belt driven from pulley 62 (Fig. 3).

The newspapers to be acted upon are fed to the machine by being piled on the table 7 (Fig. 1^a) which is provided with lateral uprights 63 and has arranged before it a rocking gage 64 supported by the lateral standards 32 and operated by the projection 65 on the upper part of the gripper. It will be understood that the gripper moves to the right in Figs. 1 and 1^a toward the newspapers on the table 7, and in doing so the projection 65 will engage the gage 64, rocking the same and bringing the newspapers in the pile into proper alinement.

The table 7 reciprocates vertically, being provided with the depending posts 66 moving in guideways 10 and provided with racks 76 with which the sector gears 77, mounted on rock shaft 36, are engaged. The rock shaft is operated by crank arm 78, connecting rod 80, and cam 79 coöperating with the follower 81 on the connecting rod 80. This mechanism is shown in detail in Fig. 10 and from that figure it will be clear that the movement of the sector gears and consequently the travel of the table 7 may be adjusted by varying the point of connection

between the connecting rod 80 and the crank arm 78, the latter being provided with a suitable elongated slot to permit this adjustment. Crank arm 78 is provided at its lower end with a perforation 161 in which is engaged a spring (shown in Fig. 1^a) to keep the follower 81 in contact with cam 79.

The table 7 is cut away centrally, as shown in Fig. 1, to admit the jaws of the grippers and is further cut away angularly at one side to provide space for the suction nozzle 67 which is connected by pipe 11 to an air pump 12 (see Fig. 3). When the table 7 descends, the end of the lowermost newspaper thereon is engaged by this suction nozzle and retained thereby when the table rises, the edge of the newspaper being slightly bent and providing an opening between that newspaper and the next above which facilitates the introduction of the separating blade or knife 22 (see Fig. 1). This knife is inserted between the lowermost newspaper and those above it in the pile to insure that the former will be seized by the separating grippers. The pump 12 may be of any usual or desired form and I have herein (Figs. 3 and 4) shown the cylinder oscillating on a journal 68 and the piston rod as driven by a crank disk 69 on shaft 70 which takes its motion through the gear 95 train 71, 72, 73, 74, 75, 45 (Fig. 2).

The separating blade 22 derives its motion from shaft 70 and is operated (Figs. 1^a and 11) by a cam 31 in the cam groove of which engages the follower 83 of a connecting rod 100 84 guided in its motion by the arms 85 embracing shaft 70. The connecting rod oscillates arm 86 which is loose on shaft 36; and in one of the openings 87 provided for purposes of adjustment in crank arm 86 is secured a rod 88 connected in its turn to the arm 89 which, as best shown in Figs. 7 and 3, is mounted on the shaft 90 which carries the separating blade 22. As best seen in Fig. 7, the rod 88 is connected to the parts 105 86 and 89, respectively, by universal joints permitting oscillation in any direction. The shaft 90 is journaled in sleeve 93 forming a part of a bracket secured to the frame of the machine. It will be understood that in each 115 cycle of the machine the blade 22 swings inwardly from the position shown in Fig. 1 and is inserted between the lowermost paper on table 7 and the overlying papers. The extent of its motion will be understood from 120 Fig. 1 by noting that the recess at the rear of the blade is designed to register with the central recess of the table, these recesses permitting the jaws of the gripper to extend in over the edge of the lowermost paper 125 without interference.

From the description so far given, it will be understood that in the initial operation of the machine the table 7 is lowered to permit the lowermost newspaper to engage the 130

suction nozzle 67. As the table again rises, the lowermost newspaper is somewhat separated from the rest and the blade 22 then swings in and completes the separation.

- 5 Meanwhile, the gripper slide 14 has been moving toward the right in Fig. 1^a and the fixed upper jaw 7 enters between the newspapers where separated and the lower jaw then closes on the newspaper through the 10 recess at the center of the front edge of the table and that in the blade, both shown in Fig. 1. The gripper then retreats toward the position shown in Fig. 1^a and as its jaws pass the stops 59 they are opened and 15 the paper is held and drawn out from the jaws by the stops. It is then free to drop down on the belts 24 which quickly carry it to the left in Fig. 1 until it engages the fingers 51 depending from the slide 14 and 20 which serve as gages to position it beneath the printing mechanism, the printing action taking place during the dwell of the slide due to the actuation thereof by a crank mechanism.

- 25 The printing mechanism here shown operates by means of address plates 94, a suitable number of which may be piled in a container or feed case 8 (Fig. 2) mounted on the transverse guide or galley 37 through 30 which the plates travel. As best shown at the bottom of Fig. 1 and in Fig. 2, a plunger plate 95 is caused to reciprocate in the slot 97 in the end of galley 37 (see Fig. 12) by means of the arm 5, and at each stroke 35 of this plunger a plate is fed from the bottom of the pile in the case 7 and moved along in the galley 37, pushing before it the plates which have previously been inserted. The plates thus fed forward come to rest 40 over the supporting projection 98 (Fig. 12) where they lie beneath the newspaper held by the stops 51. While in this position the printing hammer 28 (Fig. 1) descends and causes the plate to print on the paper 45 through the inking ribbon 112. The hammer may be operated as here shown by a cross head 160 (Fig. 1^a) supported by depending posts 200 to which a vertical reciprocating motion is given by two cams 201 on 50 shaft 132. The cross head may be held when desired in an elevated position to hold the hammer out of action by means of the latch 99 (Fig. 2).

- 55 In the present instance, the inking ribbon is carried on spools 20 and 20' (Fig. 12) and passes over guide rolls 113 and 114 which hold it in proximity to the galley 37. The ribbon may be driven from the shaft 70 (Fig. 2) which herein carries a cam operating 60 the rod 107 and through this latter the crank lever 108 provided with a pawl 109 which engages with and drives the ratchet wheel 129 carried by the sleeve or hollow shaft 110. A crank handle 111 is 65 also provided by which the ratchet may be

manually advanced when desired. The sleeve 110 (Fig. 12) is journaled in a suitable bracket and freely receives the end of shaft 115 which may be connected thereto by the double-acting clutch 29 provided on 70 sleeve 110. In Fig. 12 the clutch is shown in neutral position. If we suppose it shifted to the left into engagement with clutch disk 121 on shaft 115, the spool 20' will be driven by the bevel gears 119 and 120, the 75 gear 120 being fast on shaft 115, and wind the ribbon in the direction of the arrows in Fig. 12. On the other hand, if it is shifted to the right into contact with disk 118 which forms a part of bevel pinion 117 loose 80 on sleeve 110, the spool 20 will be operated through the bevel pinions 117 and 116 and wind up the ribbon in the contrary direction.

The entrance of each printing plate into 85 the guide or galley 37 imparts motion to all the plates therein and causes the discharge of one of the plates from the farther end. This plate will enter the receiving case 19 (Figs. 3 and 5) arranged at the 90 farther end of the galley, this case being provided with an inclined bottom, as seen in Fig. 5, so as to cause the plates to slide and stack themselves properly under the influence of gravity. The case 19, which is 95 removable, is so arranged as to descend as the plates are fed thereto. For this purpose, as seen in Figs. 5 and 3, it is mounted on a support 166 from which rises a rack 100 with which meshes a gear on the shaft of 100 ratchet wheel 13 (Fig. 3). The receiving case 19 is thus lowered with a step-by-step movement as the plates are delivered thereto.

The arm 5 which feeds the plates along the galley may be held out of action when 105 desired and for that purpose carries at its end a movable latch 96 (Fig. 13) which may engage with a notch formed in the lower part of arm 41 (see Fig. 1). To permit the arm to be thus locked out, it is 110 yieldingly operated and I have herein (see Fig. 13) shown it as oscillating about a center 105 and driven by a face cam 4 engaging the cam follower 106. A suitable spring 115 26 maintains the contact between the follower 106 and the cam 4 and it is the force of this spring which feeds the plates along the galley, as will be well understood by inspection of Fig. 1. The arm 5 can thus be locked out against the force of the spring, 120 and furthermore, in the case of any obstruction to the movement of the plates along the galley the action of the arm may be stopped without causing any breakage.

When the newspaper has been printed 125 upon, the gripper again starts toward the right, viewing Fig. 2, and in doing so the projections 51 will push it forward in spite of the contrary feeding motion of the belts 24 until it engages the fluted rollers 25 130

which carry it onward until it is delivered to the tape belts 122 (Fig. 1).

The rollers 25 are driven by belts 169 (Fig. 2) from pulley 159 on shaft 168, it-
5 self belt driven from shaft 132 which takes its motion from shaft 70 through the gears 71 and 164. The newspaper is delivered by the rollers 25 to the tape belts 122 which carry it to the folding device; and co-operat-
10 ing with these tapes 122 are rollers 123 (Fig. 3) working within the loops formed by endless tapes 167 driven from rollers 25. The function of the rollers 123 is to press down the tapes 167 and thus press the papers 15 against the tapes 122; and for this purpose they are mounted on arms 124 on a rock shaft 125 driven from a cam 126 (Fig. 2) by means of the connecting rod 128 and the crank arm 127, a spring 130 holding the 20 follower 229 in contact with the cam. The cam shaft 131 is driven from shaft 132 by the bevel gears 3. By this mechanism the rolls 123 are caused to descend intermittently and press the papers against the bands 122 which are driven from shaft 132 by sprocket 133 (Fig. 3), chain 134, sprocket 136, chain 33, sprocket 138 which is on the axle of the band wheels 23 over which the tapes 122 are trained, the tapes being maintained under 30 tension by tension rolls 140.

The papers are thus delivered to the table 137 of the folding mechanism into contact with the gage 158 (Fig. 3). The table (Fig. 1) is provided with an elongated open-
35 ing 141 through which the newspaper may be pressed by the folding blade 6 (Fig. 4). This blade is carried by the arms 142 on shaft 143 which is provided also with an arm 144 which may be adjusted by the thumb 40 screws 145 to vary the throw of the arms 142. The arm 144 is normally drawn in a clockwise direction, viewing Fig. 4, by the spring 162 and is moved against the action of the spring by the connecting rod 266 pro-
45 vided with a follower 147 co-operating with cam 30 on shaft 131.

The descent of the arm 6 presses a doubled portion of the newspaper between two rollers 148 just beneath and on opposite 50 sides of the opening 141 in the table, one of these rollers carrying a bevel pinion 149 driven by a similar pinion 34 on shaft 139. The paper will thus be fed downward and creased in its folded condition by the rollers 55 148 and will be delivered by them to one pair of the arms or paddles 15 forming a transfer wheel mounted on a shaft 163 chain-driven by sprocket 153, chain 151 and sprocket 152 which takes motion from cam 60 shaft 131 through gears 267. The paddle wheel rotates in a counterclockwise direction viewing Fig. 4 and deposits the folded news-
65 papers one by one, as received thereby, on the tapes 157 running over pulleys 16 which deliver the newspapers, folded and ready

for mailing, at the side of the machine. The tapes are here shown as driven from sprocket 153 on shaft 163 by chain 154 and sprocket 155.

The operation of the machine has been 70 described in connection with the description of the individual mechanisms and need not be repeated here.

It will be understood that the printing plates may be kept duly classified in cases 75 19 from which they may be taken and inserted in bulk in the magazine 8. After the case 19 is emptied, it is placed on the opposite side of the machine on the supporting member 166 (Fig. 5) and is refilled by the 80 plates originally therein, after impressions have been made therefrom. The plates can thus be kept in classified order without difficulty. The machine may be used for folding purposes only by locking out the printing 85 hammer 28 by means of the latch 99 whereby the cross head 160 is prevented from descending. The plate feed will also be stopped by engagement of the latch 96 with the notch formed on the lower part of arm 41, as al- 90 ready described.

I have described in detail the particular mechanisms shown in the accompanying drawings as a part of the organized machine forming a preferred embodiment of my invention. It will be understood, however, that the detailed character of this description has a descriptive rather than a definitive purpose and that the details of construction might be widely varied without 100 departing from the spirit of the invention. The principles exemplified by the specific disclosure and which I consider new and desire to secure by Letters Patent I shall express in the following claims:— 105

I hereby declare that what I claim as new and desire to secure by Letters Patent, is:

1. In a machine of the class described, a magazine for receiving a pile of newspapers or the like, a reciprocating gripper for withdrawing one therefrom, belts to receive the paper so withdrawn and a gage co-operating therewith for positioning the paper for operation of suitable mechanism thereon, means to move said gage to deliver the paper from 110 said belts and feeding means to receive the paper so delivered.

2. In a machine of the class described, a magazine for receiving a pile of newspapers or the like, a reciprocating gripper for withdrawing one therefrom, means for opening the gripper on its return stroke, belts to receive the paper from the gripper and position it for operation of suitable mechanism thereon, means moving with said gripper on 115 its forward stroke to deliver the paper from the belts.

3. In a mechanism of the class described, a magazine to receive a pile of newspapers or the like, conveyor means at opposite sides 120

thereof for moving papers in opposite directions, gages cooperating therewith and means adapted on each cycle to feed a paper from the magazine to one conveyer means 5 and to deliver a paper from said one means to the other.

4. In a mechanism of the class described, a support having a cut-away edge, separating means adjacent said cut-away portion, a 10 gripper adapted to enter said portion, a movable gage adjacent said front edge and means carried by said gripper for operating said gage.

5. In a mechanism of the class described, a 15 reciprocating support, a suction nozzle presented adjacent the edge of the support at its lower position, a separating blade arranged to move in over the edge of the support and a gripper movable to and from the 20 support.

6. A mechanism as described in claim 6 wherein the edge of the support and the blade are recessed to receive the gripper.

7. In a machine of the class described, a 25 magazine for receiving a pile of newspapers or the like, a crosshead movable toward and from the same, a gripper carried by the crosshead, means for operating the jaws of the same, belts beneath the path of the cross- 30 head and fingers depending from the crosshead and extending between the belts.

8. A machine as defined in claim 8 wherein the crosshead is actuated by a crank

and connecting rod whereby said fingers may serve as gages during the dwell of the rod 35 as the crank comes to dead center.

9. In a machine of the class described, a magazine for receiving a pile of newspapers or the like, a crosshead movable toward and from the same, a gripper carried by the 40 crosshead, means for operating the jaws of the same, stop means for ejecting the paper from the jaws, belts beneath the path of the crosshead and fingers depending from the crosshead and extending between the belts. 45

10. In a machine of the class described, a magazine for receiving a pile of newspapers or the like, a crosshead movable toward and from the same, a gripper carried by the 50 crosshead, means for operating the jaws of the same, a slotted table beneath the path of the crosshead, belts having their upper runs exposed through certain slots and fingers depending from the crosshead and working in other slots. 55

11. In a machine of the class described, a magazine to receive a pile of newspapers or the like, a reciprocating member for withdrawing papers from the pile, a plate swingably mounted before said pile and means 60 carried by said member to swing said plate whereby to align the papers in the pile.

EXEQUIEL PEDRO PAZ.
